Salomon Dunning of Brunswick, Ohio.

Letters Patent.

The schedule referred to in these Letters Patent and making part of the same, containing a description in the words of the said Salomon Dunning himself of his improvement being a wind wheel or mill, turning in a horizontal direction.

Be it known that Salomon Dunning of Brunswick in the County of Medina, now State of Ohio, have made an improvement in the useful art, being a wind wheel or mill turning in a horizontal plane and which is described as follows.

This wind wheel consists of an vertical shaft, with two wings or fans to receive the wind to turn the shaft. The upper and lower floors, and posts or uprights forming a frame to support the works; the shutters putting 1/4 for admitting the wind upon the wings.

The vertical shaft is made of any suitable size for the mill intended to be built. It is placed vertically in the center of the building, turning on quidgones, in steps or boxes. On the top of the shafts and ribs at the proper distance below are framed into the shaft twelve arms, more or less to receive the wings or fans. Or two circular platforms may be constructed of thick plank to answer the same purpose. The shaft receives its support from four posts passing through the centre of the mill framed together at the bottom by two strong beams, or cross pieces and fastened by keys or bolts on the upper platform or floor.

The upper quidgon of the shaft, turns in a box placed in a cross piece in the upper platform, and the lower quidgon turns in a box or step on the cross piece below.

There are about twelve wings or fans more or less, placed round the shaft at equal distances apart, at an angle of about 15 degrees

Dunning

with the shaft, they receive their support from the arms or wooden planks attached to the vertical shaft, before described. The shaft is turned by the wind striking upon these wings in a horizontal direction, sufficient room being left for them to turn within the frame.

There are eight outward posts more or less placed at equal distances apart, on a lower floor, made of strong plank, and divided into as many sides as there are posts. They are supported at the top by an upper floor made of the same size, strength and figures as the lower floor. Openings are made in these floors for the vertical shaft and the four posts, before mentioned, to pass; and also the cords will the weights to be hereafter described.

There are eight shutters, more or less turning on pivots, in the upper and lower floors and resting when closed against steps or beams near the shaft. These shutters are to be opened and closed for letting the wind on or off the wings or fans.

To the back of each shutter is fastened a rope or cord which passes over a pulley in the post adjoining, for opening the shutter, a weight is attached to the end of the rope for keeping the shutters open and hanging on the outside of the post. Another rope is fastened in the inside of the shutters and passes over a pulley in the post near the shaft, and through the lower floor, having a weight also attached to the end of it and is for closing the shutters to prevent the admission of wind when too strong.

On the vertical shaft is a og wheel which goes into any other wheel required for giving motion to mills or machinery.

Operation the shutters being opened on all sides, the wind strikes the wings or fans attached to the shaft and causes it to turn in a horizontal direction and gives motion to the og wheel with the machinery attached. The invention here claimed and desired to be secured by Letters Patent is the before described wind wheel particularly the wings or fans attached to the arms or bars, the shutters for letting on and off the wind, and the ropes, weights, and pulleys by which they are opened and closed. See further illustration of my invention
